(57) CLAIM

I claim the ornamental design for a bear-shaped container, as shown and described.

DESCRIPTION

FIG. 1 is a perspective top left side perspective view of the bear-shaped container with a cap installed thereon;

FIG. 2 is a front side view of the design embodiment shown in FIG. 1. The bear-shaped container has what resembles a shirt located in the chest area of the bear;

FIG. 3 is a back side view of the design embodiment shown in FIG. 1;

FIG. 4 is a left side view of the design embodiment shown in FIG. 1;

FIG. 5 is a right side view of the design embodiment shown in FIG. 1;

FIG. 6 is a top view of the design embodiment shown in FIG. 1;

FIG. 7 is a bottom view of the design embodiment shown in FIG. 1; and,

FIG. 8 is a perspective top left side perspective view of still another embodiment of the bear-shaped container with the shirt drawn in dashed lines indicating that it does not form any part of the invention.

The subject shown in dashed lines, i.e., the shirt and any surfaces of the container not shown, including interior surfaces, form no part of the claimed invention.
